MANIFOLDING AND SHEET ALIGNING APPARATUS

William Reginald Howe, Indianapolis, Ind., assignor to The Egry Register Company, Dayton, Ohio, a corporation of Ohio

Application September 29, 1939, Serial No. 297,144

23 Claims.

(Cl. 282—21)

This invention relates to improvements in manifolding devices, and more particularly autographic registers.

It is an object of this invention to devise an improved roller and paper web aligning means for use in autographic register devices so that the superimposed sheets are aligned by means inserted in the file punch holes of the superimposed sheets as the manifold sheets are moved to a new writing position.

It is a particular object of this invention to provide a novel form of aligning pin which cooperates with the web feed roller to permit the free movement of the sheets thereunder while the aligning pins are pressed thereagainst.

Another object is to devise an improved aligning pin which is adapted to coact with the file holes in the paper sheet so as to maintain proper contact therewith during movement of the web without marring or inducing buckling of the web during use of the device.

Another object is to provide an improved form of aligning pins which are equipped with individual rollers or casters and shaped to engage into the file punch holes of the paper web, which is to be written upon, as it is advanced forward to a new writing position.

Another object is to provide an improved roller and cooperating aligning pin means for manifolding devices wherein the paper sheet is aligned by the pins which are integrally attached on individual sleeves and are adapted to be friction driven by the associated paper web feeding roller mechanism.

Another object is to provide an improved paper sheet ejecting and aligning roller mechanism whereby different forms of manifold sheets can be readily accommodated.

Still another object of this invention is to provide a combined ejecting roller and coacting spring pressed sleeve member upon which is mounted the paper aligning means and cam means for spreading the paper ejecting rollers of the autographic register.

Another object is to provide an improved roller mechanism wherein fine spring adjustments are unnecessary, as changes from two to several more copies can be made without adjusting the springs.

Another object is to provide an improved roller mechanism whereby the tendency of the paper to wear the pin points is overcome by the rollers.

These and other objects and advantages will appear from the following description taken in connection with the drawings, wherein:

Figure 1 is a vertical sectional view taken lon-

gitudinally through an autographic register device, the rear portion being partly broken away, and embodying my improved roller and aligning mechanism;

Figure 2 is a sectional view taken on the line 5—2 of Figure 1;

Figure 3 is a fragmentary detail sectional view of an autographic register similar to Figure 1 showing the position of the roller and associated aligning pins when the paper web is being ejected 10 out of the machine;

Figure 4 is a fragmentary plan view of a portion of the register with the cover broken away showing the roller and paper web aligning pin mechanism in position corresponding to that 15 shown in Figure 3;

Figures 5, 6 and 7 are detail perspective views showing different relative positions of the aligning pins and paper web illustrating the coaction of the aligning pins with the paper web file holes 20 during movement of the paper web through the device.

General construction

In Figures 1, 2 and 3 there is illustrated an 25 autographic register device which embodies the improved roller and web aligning pin mechanism of this invention which comprises a casing 8 mounted on a base 9. Rearward hinged cover 10 forms an arm support and writing opening adjacent which superimposed paper web forms 11, which are to be written upon, are moved. Suitably positioned beneath the cover is a writing table 12 for supporting the paper web 11.

The manifold web sheet 11, as illustrated in 35 Figures 1 and 3, comprises a plurality of superimposed paper sheets having printed forms thereon and having spaced file holes 13 which are adapted to cooperate with the aligning pin means on the web feed roller mechanism to properly align the sheets, as will be hereinafter more fully described.

Preferably the manifold paper comprises a continuous web of superimposed sheets fan-folded in a pack which is placed in a compartment provided for this purpose at the rear of the register. In use the manifold paper web is fed forward over the writing table and after writing upon is advanced so as to separate the original paper sheet 11a and the copy sheet forms 11b; the 50 former being ejected and the latter retained in the forward compartment 14 of the device as illustrated in Figures 1 and 3.

A cover or lid 16 is pivoted at the forward end of the register on the transverse rod 17 and is 55

arranged to engage under the U-shaped hood section 18 of the cover 10, space being provided between the hood and lid 16, as at 19, to permit the free movement of the web sheet 11a outward 5 over the lid 16 during use of the machine.

The rear wall of the compartment 14 comprises a Z-shaped member 20 which is preferably made in one piece and is provided with an inclined front portion 21 which is arranged to form a 10 guide and support for the used manifold sheet material 11b. Within the storage compartment 14 are positioned the adjustable upstanding wall members 22 which are fastened in place by suitable set screws 23. Additional set screw holes 15 24 are provided for changing the relative position of the members 22 so as to vary the space defined by the walls. Depending from the underside of the lid 16 is a swingable copy sheet guide finger 25.

20 *Measuring and aligning mechanism*

The mechanism for drawing the writing paper web through the device a predetermined measured distance at intervals to expose a new writing form for recording different transactions comprises a master gear 30 which is arranged to drive the pinion 32 on a shaft 33. Also fixed to rotate with the gear pinion 32 is a gear 34 of larger diameter which meshes with the gear 36 30 of the lower roller sleeve member 31 keyed to the roller shaft 38. Gear 36 in turn drives the gear 39 mounted on the upper coating web feeding roller shaft 40. The lower roller shaft 38 is suitably journaled at each end in the side walls of 35 the device as shown in Figure 2.

A spacing roller member 41 is loosely mounted upon the upper roller shaft 40 which is loosely journaled in the openings 42 in the side walls of the register. Roller shaft 38 is provided with an 40 enlarged knurled sleeve 43 for engaging the underside of the manifold paper sheet. The knurled sleeve member 43 is keyed to turn with the shaft 38 by means of the pin 43a. Spacing sleeve members 44 and 45 are positioned opposite 45 the end of the knurled sleeve member 43 and are fixed to rotate with the shaft 38 by means of the pins 44a and 45a respectively. The spacing sleeve members are suitably shaped to function as lateral guide supports for the manifold paper 50 web as it passes between the rollers.

The upper roller shaft 40 is provided with a knurled sleeve member 50 which is keyed to the shaft 40 by means of the pin 50a and co-operates with the lower knurled sleeve 43 for drawing the 55 paper web therealong. Spaced at opposite sides of the knurled sleeve 50 are the paper aligning guide sleeve members generally designated 51, which are yieldably urged outward from the knurled roller member 50 by means of the 60 springs 52. The outer ends of the sleeve members 51 terminate in a boss 53 which is adapted to telescopically engage over the inner end of the cylindrical sleeve ring members 54 and 55 respectively. Sleeve 54 is free to rotate on the 65 shaft 40 and frictionally engages the side walls of the gear 39. Similarly sleeve 55 rotates on the shaft 40 and frictionally contacts the side wall of the spacer member 56 positioned on the 70 opposite end of the roller shaft 40.

75 Integral with the boss portions 53 of the web aligning sleeve members 51 are depending segmental sector cam surface means 58 which are adapted to be rotated in engagement with the cutaway sleeve portions 59 of the spacer guide members 45 mounted on the lower roller shaft

38. On the inner boss section 60 of the sleeve members 51 are fixedly attached the web aligning pins generally designated 65. The pins, as illustrated in Figures 2 and 7, comprise tapered conical extensions 66 having a bifurcated outer 5 end forming an axial support for the wheel or roller member 67 equipped to rotate on the axial means 68 journaled near the end of the bifurcated member 66. The pin extension 66 and attached roll 67 are of a size such that they will 10 readily enter the spaced file holes 13 in the manifold web papers 11 as the superimposed sheets are moved along between the gripper rolls 43 and 50 during use of the register.

The tension in the spring members 52 is such 15 as to provide a friction drive for the sleeve members 51 through the sleeve and associated contacting parts engaging the shaft 40. The force of the springs, however, is not so great as to tear the web or apply unnecessary pressure on 20 the pins forcing them to gouge into the paper web sheet passing between the rolls. It will be understood that the aligning pins 65 will be spaced apart a proper distance corresponding to the space between the punch holes 13 on the 25 manifold paper sheets used in the register device.

Upon rotation of the master gear 30 the pin 70, fixed to the side walls of the gear 30, is brought into contact with the lever 72 along the outer cam surface 72a, as illustrated in Figure 1. 30 The lever 72 is pivoted on the transverse shaft 73 journaled in the side walls of the register and the forward end of the lever is curved around the lower roller sleeve member 45 and the uppermost 35 end portion 75 is arranged to act as a stop means 40 for arresting the rotation of the depending cam sector 58 on the aligning sleeve members 51 while aligning of the sheets is in progress. Yieldable means, not shown, are suitably positioned to maintain the lever 72 yieldably in position so 45 that its cam surface 72a will be contacted by the pin 70 during its course of movement. This permits rotation of the cam sector 58 out from between the gripper roll members to cause them to grip the web immediately after the aligning of 50 webs by pins 65 has been effected. A similar lever is positioned on the opposite side of the register device for arresting the movement of the adjacent depending cam sector. In this manner both aligning pins are momentarily held at their lowermost position while they are engaged in the punch holes of the web during the aligning of 55 the superimposed webs.

Additional manual means is also provided for moving the knurled rolls 50 and 43 apart. This mechanism comprises a cam shaft 80 which extends through the lifting plates 81 on either side of the register, which in turn are yieldingly held by the springs 82 in their lowermost position to cause the upper roller to remain in its lower 60 clamping position in the normal movement of the webs. The bracket 83 on the side walls of the register serves as a support for the lifting plates. A stud 84 is carried in the lower ends of the lifting plates 81 and also abuts through the spring 65 82 and the stationary bars 85 on the side walls of the register. The cam shaft 80 which passes through these lifting plates is provided with a cam surface 80a and is adapted to be independently actuated by the stud by rotation of the button 86 attached to the end of the shaft 80 on the outside of the register when it is desired to spread 70 the knurled rollers 43 and 50 for threading the manifold paper in the machine before starting 75

its operation. The backward movement of the master gear 30 is prevented by the pawl 88.

The hood section 18 of the cover 10 has arranged on either side of the front of the hood 5 depending eye members 90 for receiving the locking hooks 91 which are connected to the shaft 92 which is pivoted in the side walls of the register. The shaft 92 is provided with an operating button 94 which is positioned on the outside of the register for unlocking the hooks 91. The hooks are maintained yieldably in locking position by the spring 95 connected to the side wall of the register at 96 and to an arm 97 which in turn is fastened to the shaft 92. The arm 97 rests upon the shaft 80 as a stop. Rearward movement of the locking hooks 91 is prevented by the positioning of the bell crank 99 which is pivoted on the register at 100. The bell crank has one arm adapted to engage the back of the hook member 91 and has the other arm engageable by the lock 101 when the same is in locked position.

Method of operation

25 When the crank or handle used for actuating the device is actuated while the parts are in the position shown in Figure 1, the web ejecting rollers 43 and 50 advance the web forward through the register and the sleeve members 51 are rotated carrying the aligning pin members 65 around in engagement with the web. The sleeves 51 then remain stationary and in sliding contact with the shaft 40 upon further rotation of the web advancing rollers 43 and 50. Pins 65 rest lightly upon the surface of the web until the file holes 13 in the web are moved under the aligning pins, whereupon the pins drop down into the file holes and are carried around upon further rotation of the sleeves 51 in position between the rolls. At the same time the depending cam surfaces 58 on the sleeve aligning pin members 51 are rotated in contact with the lower sleeve member 59 raising the gripper shaft roll 40, releasing the grip of the knurled rollers 43 and 50 on the web. The relative position of the pin 65 and cam 58 on the sleeve members 51 is such that the cam 58 is advanced between the rollers 43 and 50 slightly ahead of the pins. Thereafter, upon further rotation the aligning pin members 65 shift the superimposed webs in alignment as the tapered pins advance to their lowermost position in the file holes of the superimposed sheets.

While in the aligned position the writing form 55 of the manifold sheets is in position on the writing table so that notations may be made thereon. Thereafter, upon actuation of the handle for rotating the master gear 30, the pin 70 contacts the lever 72 releasing the cam sectors 58 to permit the aligning pins 65 to rotate around with the shaft 40 so as to be disengaged from the file holes and at the same time permit the movement of the gripper rolls 43 and 50 to a clamping position on the web. This is brought about by movement 60 of the cam sectors 58 out from between the rolls, whereupon the paper web sheets are again clamped and the web may be moved into a new writing position. It will be noted that the cam and aligning pins are not mechanically connected to the shaft 40 being merely frictionally dragged around upon rotation of the upper roller shaft 40 due to the force of the springs 52 which yieldably maintain the sleeves 51 in engagement with the roller shaft members.

75 It will be understood that various sizes of

aligning sleeve members 51 may be employed for accommodating the different lengths and types of manifold web sheets having different sized file holes, forms or similar pin engaging means.

It will be further understood that this invention is not limited to the exact details of construction shown and that such modifications as may be necessary to adapt it to varying conditions and uses are contemplated to be within the scope of this invention.

Having thus fully described my invention, what I claim as new and desire to secure by Letters Patent is:

1. In a manifold register having a plurality of superimposed manifold sheets with spaced perforations and cooperating sheet ejecting means, the improvement comprising aligning pin means having rollers mounted on the outer ends for engaging into the perforations in said sheets carried by one of said ejecting means, and means 15 for driving the ejecting means independently of said aligning pin means.

2. In a manifold register device having a plurality of superimposed manifold sheets with spaced perforations therein and cooperating means for advancing said sheets through said device, the improvement comprising tapered conical aligning pin means having outer independently movable portions adapted to be inserted in said perforations to align said superimposed 25 sheets, said pin means being carried by one of said sheet advancing means, and means for driving the sheet advancing means independently of said aligning pin means.

3. In a manifold register device having a plurality of superimposed manifold web sheets with spaced perforations therein and means to eject said sheets, means to render the ejecting means inoperative, means to align the superimposed sheets comprising spaced protuberances having 30 casters mounted thereon, said sheet aligning means being shaped to engage into apertures in said sheets, and means for driving the ejecting means while said aligning means are stationary.

4. In an autographic register having a plurality of superimposed manifold paper webs with spaced perforations therealong, the improvement comprising a roller for ejecting the paper webs, said roller having sleeve means mounted thereon carrying aligning pins which are adapted to be 40 projected through the apertures in said sheets during aligning thereof, said aligning pin means comprising an outermost paper web engaging portion which is movable with respect to the body portion of said pin.

5. In an autographic register having a plurality of superimposed manifold paper webs with spaced perforations therealong, the improvement comprising a roller for ejecting the paper webs, said roller having sleeve means mounted thereon 50 carrying aligning pins which are adapted to be projected through the apertures in said sheets during aligning thereof, said pins having rollers mounted on the outer ends for engaging the forward margins of the apertures in said superimposed manifold paper webs.

6. In an autographic register having a plurality of superimposed sheets with spaced perforations, the improvement comprising aligning pin means mounted on a roller shaft and yieldably engaging therewith, said aligning pins comprising independently movable pin point members, said pins being adapted to be yieldably held against the surface of the superimposed sheets and be inserted in said perforations to align said 75

superimposed sheets as the same are moved to a new writing position.

7. In an autographic register having a plurality of superimposed manifold web sheets with spaced perforations, ejecting means comprising superimposed rollers having knurled paper gripping surfaces, arcuate shaped aligning pin means mounted on a sleeve which cooperates with the ejecting means to permit the free movement of said superimposed paper sheets while the aligning pins are pressed thereagainst, said pins comprising a body portion which is adapted for insertion into said perforations for bringing about alignment of the superimposed sheets and having an independently movable pin point section on said body portion.

8. In an autographic register having a plurality of superimposed manifold paper sheets with spaced perforations, the improvement comprising a combined paper sheet ejecting roller and aligning means, said aligning means comprising a protuberance having a tapered body portion for fitting into said perforations to align the superimposed sheets, said protuberances having individual rollers mounted on the outermost part to provide rolling contact with said paper web sheet as it is advanced forward to a new writing position.

9. In an autographic register having a plurality of superimposed manifold paper sheets with spaced perforations therein, an improved paper web ejecting roller means and cooperating web aligning means, said aligning means comprising pins which are integrally attached on individual sleeves, said sleeves being friction driven by said paper web roller ejecting means, said pins comprising tapered wall portions which are adapted to engage the side walls of the perforations to move the superimposed sheets longitudinally to align them and said pins having means thereon for providing a rolling contact with said manifold paper as the same is moved along from one set of perforations to the next.

10. In an autographic register, ejecting means for a plurality of superimposed sheets of paper having aligned holes therein, the improvement comprising ejecting roller means having a pair of sleeve members operatively connected to the roller, said sleeve members having pins thereon adapted to engage in the holes of said sheets and align them as said sheets are advanced through said register, said pin means being of the same shape in cross-section as said holes and comprising independently rotatable means pivoted on the outermost end portion of said pin means, said sleeve members being rotated by variable friction means associated with said ejecting roller means.

11. In an autographic register having a plurality of superimposed sheets with spaced perforations, cooperating roller means for engaging said superimposed sheets and ejecting the same, aligning pin means comprising a substantially frictionless paper contacting head portion and a body section having side walls engageable with the walls of said perforations, said aligning pin means being mounted on sleeves and carried loosely on the shaft of said roller means, means to drive the ejecting rollers and means to render the same inoperative at predetermined intervals while said pin aligning means are entering and aligning said sheets, said frictionless paper contacting head portion consisting of independently movable means pivoted on the outermost end portion of said pin means.

12. In an autographic register having a plu-

rality of superimposed sheets with spaced perforations, superimposed rollers adapted to grip said sheets and eject the same upon rotation of said rollers, the improvement comprising aligning pin means carried by one of said rollers, said aligning pins comprising arcuate shaped protuberances having castors mounted on the ends thereof, means for spreading said rollers at intervals, means for moving the aligning pins into the path of the apertures in said sheets as said sheets are advanced through said register, and means to permit the independent movement of said pins relative to said ejecting roller means.

13. In an autographic register, the improvement including a manifold sheet aligning member, said member comprising a cylindrical body adapted to be mounted as a sleeve on a shaft, said cylindrical body having a pin fixed therein, said pin comprising arcuate shaped side walls and having an independently movable outer end portion for reducing the friction between said pin and the manifold sheet being aligned.

14. In an autographic register, the combination with a paper sheet ejecting roller means of a sheet aligning member, said member comprising a hollow body having a pin roller carried thereby which is adapted to engage in spaced file holes of paper sheet for aligning the same, said body having an integral depending cam sector adapted to coact with said ejecting roller means on said autographic register to render the same inoperative at intervals during the use of said register.

15. In an autographic register, having a plurality of superimposed spaced sheets with perforations, separating means, a lower roller shaft, an upper roller shaft cooperating therewith for ejecting said sheets, a sleeve means comprising a cam and a sheet aligning pin roller means mounted on said upper roller, yieldable means on said upper roller for providing frictional engagement of said sleeve with said upper roller shaft means, and means to independently drive the lower roller shaft means.

16. An autographic register having, in combination, means for feeding a plurality of superimposed strips of paper with transverse creases dividing the strips into sections and holes at one end of each section, means for drawing the superimposed paper strips as a unit to a writing position, strip aligning pin roller means operatively connected with said feeding means adapted to engage in said holes as said strips are moved along, and means for rendering inoperative said feeding means while said pin roller means is engaged in the holes of said strips to align said strips.

17. An autographic register having, in combination, friction rollers mounted on cooperating shafts for feeding a plurality of superimposed continuous sheets of paper having spaced writing sections provided therealong, said sections having holes at one end of each section, means for aligning said superimposed sheets comprising an independent sleeve member mounted on the uppermost feeding roller shaft and yieldingly spaced from said roller portion having sheet aligning pin roller means for engaging in said holes, said sleeve means comprising means for rendering said feeding rollers inoperative during the aligning of said superimposed sheets.

18. In combination with a pair of coacting gripper rollers for feeding a plurality of superimposed strips of paper having writing sections spaced therealong of a plurality of rotatable

- 5 sleeve members operatively connected by spaced
sleeve having means for rendering said feeding
means mounted thereon for rendering said gripper roller
inoperative at intervals and independent
means comprising spaced pin rollers mounted on
said sleeve for aligning said strips while said gripper
rollers are rendered inoperative.
19. In combination with means comprising co-
acting rollers for feeding superimposed strips of
10 material having spaced sections for writing ar-
ranged thereon, of rotatable sleeve means fric-
tionally actuated by one of said rollers carrying
means for rendering said feeding rollers inactive
and having independent means mounted on said
15 sleeve for engaging said superimposed strips and
aligning the same while said feeding rollers are
rendered inactive, said strip aligning means com-
prising a tapered pin having an outer independ-
ently movable portion contacting said strip.
20. In an autographic register for use with a
plurality of superimposed strips of paper having
spaced writing sections thereon and holes at one
end of each section, of coacting rollers for feed-
ing said superimposed strips, means comprising
25 a sleeve member axially mounted on one of said
- rollers and operatively connected thereto, said
sleeve having means for rendering said feeding
rollers inoperative and independent means on
said sleeve for aligning said superimposed strips
while said strips are moved along, said strip 5
aligning means comprising a pin having a roller
mounted thereon engageable with said strip.
21. In manifold sheet aligning mechanism, an
aligning pin comprising an arcuate body portion
as the means for aligning and having a roller 10
mounted thereon, said roller being arranged to
project from the end of said pin.
22. In manifold sheet aligning mechanism, an
aligning pin comprising a body portion with side
wall aligning means and having a roller mount- 15
ed thereon, said roller being journaled in the
outermost end portion of said aligning pin.
23. In a feeding and aligning mechanism for
autographic registers, feeding rollers, means for
separating said rollers, aligning means compris- 20
ing a pin with a roller on the end thereof adapted
to engage paper sheets by rolling thereon and
with holes in said sheets by insertion of said pin
means therethrough.

WILLIAM REGINALD HOWE. 25
